UNITED STATES PATENT OFFICE.

ROBERT H. EMRY, OF BRIGHTON, IOWA.

LATCH FOR GATES AND BARN-DOORS.

1,249,052.

Specification of Letters Patent. Patented Dec. 4, 1917.

Application filed April 4, 1917. Serial No. 159,699.

To all whom it may concern:

Be it known that ROBERT H. EMRY, citizen of the United States of America, residing at Brighton, in the county of Washington, State of Iowa, has invented certain new and useful Improvements in Latches for Gates and Barn-Doors, of which the following is a specification, reference being had therein to the accompanying drawing.

This invention relates to a latch for gates and barn doors and has for its principal object the production of a latch which is so formed that when in a locked condition any stress upon the latch will be off-center with respect to the pivoted point of the latch lever thereby preventing the latch from accidentally unlocking.

Another object of this invention is the production of a latch for gates and barn doors wherein the latch lever is provided with a loop extending at right angles to the body, this loop being adapted to pass through a looped retainer whereby a padlock may be secured to the loop for holding the latch lever in a locked position, this loop also acting as a grip for facilitating the springing of the latch lever.

A still further object of this invention is the production of a latch for gates and barn doors wherein the latch is pivotally mounted upon the latch lever so as to cause a friction or binding action between the latch and latch lever for facilitating the removal of the latch from the keeper when the latch lever is swung in the proper direction.

With these and other objects in view this invention consists of certain novel combinations, constructions and arrangements of parts as will be hereinafter fully described and claimed.

In the accompanying drawings:

Figure 1 is a side elevation of the latch shown in a locked position.

Fig. 2 is a side elevation of the latch illustrating the manner in which the same is swung for removing the latch from the keeper.

Fig. 3 is a top plan view of the latch.

Fig. 4 is a vertical section taken on the line 4—4 of Fig. 1.

Fig. 5 is a sectional view of the keeper taken on the line 5—5 of Fig. 2.

Fig. 6 is a detailed perspective view of the rear side of one end of the latch lever.

Referring to the accompanying drawings

by numerals it will be seen that the latch lever 1 comprises an elongated body which is pivoted by means of a screw or other securing member 2 upon a door or gate 3. 60 This latch lever 1 is provided with a plurality of openings 4 through which extend the tongues 5 of the longitudinally extending reinforcing rib 6. This rib 6 is positioned upon the body 1 for holding the same 65 against opening or springing and since the tongues 5 are clamped upon the inner surface of the latch lever 1 as shown in Fig. 6, the rib will be held against accidental displacement. The other end of the latch 70 lever 1 has a grip 7 formed thereon, this grip being bent so as to extend at a right angle to the latch lever 1 as shown clearly in Fig. 6. This grip 7 is provided with an enlarged opening 8 for purposes to be hereinafter set forth.

It is of course obvious that a bearing washer 9 may be carried upon the screw 2 being interposed between the door or gate 3 and the latch lever 1 for providing a better 80 bearing for the pivoted end of the latch lever 1.

The latch 10 is elongated and has a hook 11 formed intricately upon one end. The opposite end of this latch 10 is provided with 85 an enlarged head 12 which is carried upon the pivot bolt 13 supported upon the latch lever 1. A bearing washer 14 is also carried upon the pivot bolt 13 upon the outer side of the head 12 as shown in Figs. 2 and 90 3 and in this manner positively holds the latch upon the latch lever. The latch is bent slightly intermediate its ends so as to pass slightly to one side of the pivoted end of the latch lever 1 when the latch is in a 95 locked condition as illustrated in Fig. 3, and in this manner forms a binding connection in combination with the head 12 held by the bolt 13 and washer 14.

The keeper 15 is carried upon the door jamb or gate post 16 as shown in Figs. 1, 2, and 5. This keeper 15 has its body portion 17 spaced from the outer surface of the jamb or post 16 as shown clearly in Fig. 5. An offset lip 18 is formed upon the body 17 and 100 this lip 18 terminates in an inwardly extending spur 19. A finger 20 extends from the opposite end of the body 17 projecting in the same direction as the spur 19. This finger 20 extends from the jamb or post 16 105 so as to permit a bearing washer 21 to occupy position thereon by which a head 22

is held upon the finger 20 for holding the finger from being accidentally drawn from engagement with the jamb or post 16. The spur 19 is forced into the jamb or post for assisting in holding the opposite end of the body in its correct position, while the screw 23 is passed through the body 17 adjacent the end upon which the lip 18 is formed and this screw 23 passes into the jamb or post, thereby positively retaining the keeper in a set position upon the jamb or post.

The grip loop retainer comprises a body 24 which bears upon the door or gate 3 and is held in position by means of the screw 25 passing therethrough and into engagement with the door or gate as shown clearly in Fig. 4. This grip loop retainer has a spur 26 formed upon the lower end of the body 24 which also digs into the door or gate for holding the grip loop retainer against accidental pivotal movement when the screw has been passed through the body 24 and into engagement with the door or gate. This body 24 is provided with an offset vertical projection 27 constructed so as to be spaced from the surface of the door or gate 3 as shown in Figs. 3 and 4. The flange 28 is formed upon the upper end of the projection 27 and extends at right angles to this projection. The elongated slot 29 is formed in the flange 28 and the offset projection 27 extends longitudinally through this means as shown in Figs. 2 and 3.

When this latch is in use the latch lever is pivotally mounted upon the door or gate and the keeper is fixedly mounted upon the jamb or post in the manner herein specified. Owing to the binding action of the latch upon the latch lever the latch lever may be swung over toward the keeper thereby directing the latch so as to cause the hook 11 of this latch to pass downwardly through the keeper as illustrated in dotted lines in Fig. 2. The operator may then simply press upon the latch so as to prevent the latch from being swung from engagement with the keeper as the latch lever is swung downwardly. It will be noted by referring particularly to Fig. 2 that the screw 12 is carried nearer the central axis of the latch lever 1 than is the bolt 13 for this bolt is positioned farther toward the lower side edge of the latch lever 1. As a consequence, when the latch lever is swung to a closed position the stress imparted by the engagement of the latch with the keeper and with the bolt 13 will be imparted to the latch lever below the horizontal plane of the pivot of the latch lever and because of this, the center of the pivot being mounted upon the latch lever, the latch lever will be prevented from swinging to an open position. The other end of the latch lever is swung so as to fit partially upon the offset portion 27 of the body 24 of the grip loop retainer there-

by permitting the grip loop 7 to extend longitudinally through the slot 29 of the grip loop retainer as illustrated clearly in Figs. 1 and 4. At this time a hasp padlock may be passed through the opening 8 formed in the grip loop 7 thereby holding the latch lever in a locked position and thus causing the latch to be held in engagement with the keeper. Of course, when the padlock is removed from engagement with the grip loop 7 the grip loop may be pushed upwardly, or the rib 6 may be gripped for swinging the latch lever 1 upwardly thus causing the end of the latch lever to move from under the latch 10 whereby the binding action caused by the latch passing over and to one side of the latch lever will present a binding action which will lift the latch from engagement with the keeper when the latch lever is swung upwardly. In this manner it will be seen that the latch will be automatically moved from the keeper simply by an upward and downward movement of the latch lever.

From the foregoing description it will be seen that a very simple and efficient latch for gates and barn doors has been produced wherein the offset stress of the latch upon the latch lever will hold the latch from accidentally opening when in operation while the engagement of the grip loop and grip loop retainer will positively hold the latch lever in a closed position when the latch is locked.

What is claimed is:

1. In a device of the class described, the combination of a latch lever, a latch pivotally mounted upon said latch lever, a keeper, a grip loop formed upon said latch lever and extending at right angles thereto, a grip loop retainer comprising a body having an off-set projection terminating in a flange extending to one side thereof, said projection and flange having a longitudinal slot formed therein, and the outer end of said latch lever being adapted to be moved into engagement with the inner portion of said projection so as to constitute a binding action for holding said latch lever against accidental movement, said grip loop passing through said slot at which time said latch will engage said keeper.

2. In a device of the class described the combination of a latch lever, a latch pivotally mounted off-center upon said latch lever, a keeper, a grip loop formed upon and extending at right angles to said latch lever, said grip loop having an enlarged opening formed therein, a grip loop retainer comprising a body having a projection, a flange formed upon said projection and extending at right angles thereto, said flange and projection having a longitudinal slot, said grip loop passing through said slot, said latch lever being adapted to be moved

so as to bring said latch into a binding engagement with said keeper, said grip loop being adapted to permit a securing means to be passed therethrough whereby said latch lever will be held from being accidentally moved from engagement with said grip loop retainer.

3. In a device of the class described the combination of a latch lever, a latch pivotally mounted upon said latch lever, a keeper, said latch being slightly bent intermediate its ends so as to engage a handle extending from the end of said latch lever, whereby a binding action is produced between said latch lever and said latch thereby causing said latch to move as a unit with said latch lever when it is desired to remove said latch from engagement with said keeper, said latch being adapted to be held in engage-

ment with said keeper while the latch lever 20 is being swung to a set position when it is desired to secure the latch in engagement with said keeper, said latch lever having openings formed therein, a rib positioned upon said latch lever, tongues extending 25 from said rib and projecting through said openings, said tongues being clamped upon said latch lever for holding said rib against displacement, a grip loop formed upon said latch lever, a grip loop retainer having a 30 slot formed therein, said grip loop passing through said slot whereby securing means may be passed through said grip loop for holding the latch lever from being accidentally moved.

35 In testimony whereof I hereunto affix my signature.

ROBERT H. EMRY.
